UNITED STATES PATENT OFFICE.

OSCAR BROPHY, OF PHILADELPHIA, PENNSYLVANIA.

ELECTRIC INDUCTION-FURNACE.

1,296,752.

Specification of Letters Patent. Patented Mar. 11, 1919.

Application filed June 12, 1918. Serial No. 239,538.

To all whom it may concern:

Be it known that I, OSCAR BROPHY, a citizen of the United States, residing in Philadelphia, Pennsylvania, have invented Electric Induction-Furnaces, of which the following is a specification.

One object of my invention is to provide a relatively simple, efficient and substantial form of electric furnace which shall be characterized by the novel form of its molten metal secondary as well as by the position and form of its primary relatively to said secondary;—the invention especially contemplating the mounting of the primary and secondary elements of the furnace in such relation as will insure brisk circulation of the molten metal.

I further desire to provide an induction furnace in which the primary and secondary elements are so constituted and assembled that the molten metal is caused to circulate by reason of the repulsion exerted by the primary winding upon the secondary as well as by reason of the cutting of the molten metal at definite points by relatively large numbers of lines of force.

These objects and other advantageous ends I attain as hereinafter set forth, reference being had to the accompanying drawings in which,

Figures 1 and 2 are respectively front and side elevations, to some extent diagrammatic, illustrating the preferred construction of an induction furnace made in accordance with my invention;

Fig. 3 is a plan of the furnace shown in Figs. 1 and 2.

Fig. 4 is a diagrammatic side elevation of a modified form of my invention; and

Fig. 5 is an elevation, partly in vertical section, further showing the structure of Fig. 4.

In the above drawings, the core 1 of the transformer is in the form of an open rectangular frame having between the middle parts of its top and bottom a branch 2 on which is mounted the primary winding 3.

The refractory structure 15 for the reception of metal to be operated on in my furnace, has a main cavity or basin 4 shown for convenience as having the form of a vertical cylinder, from the flat bottom of which a tube-shaped cavity extends downwardly.

The core 1 which is shown as of the shell type, is so mounted with regard to the body of metal 5 in this cavity that its branch 2

extends coaxially thereof and in order to permit of the passage of the top horizontal member of the core, there are formed in the tubular body of metal constituting the secondary of the furnace, two transverse upwardly flaring openings 6 at opposite points thereof. The relative positions of the metal shell or tube 5 and the primary winding are such that about one-third of the length of the primary winding extends below the plane of the bottom of the molten metal secondary which has the form of a ring surrounding the winding 3 and connected to the basin or main body of metal through the depending legs or branches.

By reason of the above described construction, when alternating current from a suitable source is supplied to the terminals of the winding 3, there is induced in the secondary provided by the tubular body of molten metal 5 a current of large volume and small pressure which shortly melts said metal and maintains it in a highly heated molten condition.

Owing to the extension of the axial branch 2 of the core and its winding below the plane of the bottom of the molten secondary, there is exerted upon the latter an upward repulsive force which is a maximum adjacent the points 8 by reason of these lying in the plane of the core, with the result that the metal is caused to briskly circulate both by reason of the cutting of the magnetic field through these points and also because of the above noted repulsive action.

The molten metal 5 also tends to circulate since the heat generated by reason of its resistance to the current flow induced in it, maintains its temperature above that of the metal in the main body or basin 4, and the hotter metal tends to rise through portions of the branches and be replaced by relatively colder overlying metal.

From the above description it will be understood that not only by reason of the peculiar form of the secondary constituted by the molten metal, but also because of the downward extension of the winding 3 below the bottom of this secondary, there is insured a strong circulation of the molten metal which is most active at the points 8 where the cross section of the metal is least and where the possibility of choking otherwise the greatest.

In that form of my invention shown in Figs. 4 and 5, I have made the body of molten

- metal constituting the secondary project below the main metal body in a V-shaped mass 10 whose branches or arms connect with opposite sides of the bottom of said main body 5 of metal. Said secondary which preferably has a flat laterally elongated section, extends through the central opening of the transformer core 11 which in this case is of the shell type and so mounted that its lower member extends immediately adjacent the lowest part of the metal 10. The core 11 has its winding divided into two parts 12 and 13 of which the first is placed on the upper cross member of the core while the latter is on the lower core member and is wound with a less number of turns and oppositely thereto in order that it shall exert a repulsive force on the adjacent portion of the metal 10 so as to cause circulation thereof.
- 10 I claim:
1. An induction furnace consisting of a core having a branch; a primary winding for said core; and a secondary in the form of a tubular body of molten metal substantially coaxial with said core branch and having opposite portions cut away to permit passage of portions of said core.
2. The combination in an induction furnace of a substantially rectangular core supported in a vertical plane and having a vertically extending branch; a primary winding for said core; a tubular body of molten metal constituting the secondary of the core and mounted substantially coaxial with the central branch thereof, opposite portions of the secondary being removed to permit of passage of the top portion of the core; with a main body of molten metal connected to that of said tubular body of metal.
3. The combination in an induction furnace of a substantially rectangular core; a primary winding for said core; a tubular body of molten metal constituting the secondary of the core and mounted substantially coaxial with the central branch thereof, opposite portions of the secondary being removed to permit of passage of the top portion of the core; with a main body of molten metal connected to that of said tubular body of metal.
4. The combination of a main body of metal; a tubular body of metal extending downwardly from the bottom of said main metal body and having oppositely placed openings therein; with a transformer core having a portion extending through the openings of said tubular body of metal and including a member extending substantially coaxial therewith; with a primary winding on the core.
5. The combination of a substantially rectangular core having a central member; a tubular body of metal constituting a secondary for said core and mounted coaxial with the central member thereof, said body

of metal being cut away at opposite points to permit of passage of a horizontally extending portion of the core; with a primary winding for the core mounted on the central branch partially within the tubular secondary.

6. The combination of a substantially rectangular core having a central member; a tubular body of metal constituting a secondary for the core and mounted coaxial with said central member, said body of metal being cut away at opposite points to permit of passage of a portion of the core; with a primary winding for the core mounted on the central branch within the tubular secondary and extending below a plane of the bottom of said secondary.

7. The combination in an induction furnace of a tubular body of metal constituting a secondary, having openings in opposite portions thereof; a transformer core; and a primary winding mounted on said core in position to exert an upward repulsive force on the metal constituting the secondary.

8. The combination in an induction furnace of a tubular body of metal, having oppositely placed openings; a primary winding; a transformer core for said winding mounted in a plane including the longitudinal axis of said tubular body of metal and extending through the openings thereof in position to cause a relatively large number of lines of force to intersect said body of metal at definite points.

9. The combination in an induction furnace of a body of metal to be treated including a main portion, a tubular portion and oppositely placed branches connecting said portions; a transformer core having a member extending between said branches and a second member extending coaxially with the tubular portion of said metal; and a winding on said latter member of the core, extending below the plane of the bottom of the tubular portion of the metal.

10. The combination in an induction furnace of a structure having a cavity adapted to contain a main body of metal to be treated and including also an auxiliary cavity for said metal connecting with the main cavity at not less than two points; a transformer having its core mounted to extend between a part of the auxiliary cavity and the main cavity of the structure; and a winding on the core positioned to cause circulation of the metal in the auxiliary cavity.

11. The combination in an induction furnace of a structure having a cavity adapted to contain a main body of metal to be treated and including also an auxiliary cavity for said metal connecting with the main cavity at not less than two points; a transformer having its core mounted to extend between a part of the auxiliary cavity and the main cavity of the structure; and a winding on

the core positioned to exert a repulsive action on certain of the metal in said auxiliary cavity to cause circulation thereof.

12. The combination in an induction furnace of a containing structure having main and auxiliary cavities for molten metal; a core; and a winding for the core mounted to exert a repulsive action on the metal in the auxiliary cavity such as will force it out

of the same into the main cavity, the core 10 being positioned relatively to the metal in the auxiliary cavity to cause magnetic lines of force to cut through the same at definite points and thereby cause relatively intense circulation at said points.

15 In witness whereof I affix my signature.

OSCAR BROPHY.
